POWER LAWN MOWER

Henry de S. Lauve, Grosse Pointe, Mich., assignor to Fairbanks, Morse & Co., Chicago, Ill., a corporation of Illinois

Application June 12, 1958, Serial No. 51,328

Term of patent 14 years

(Cl. D40--1)

Fig. 1

Fig. 1 is a perspective view of a power lawn mower taken from the front and left side showing my new design;

Fig. 2 is a perspective view of a power lawn mower taken from the rear and right side thereof.

The dominant features of my design reside in the portions shown in full lines.

I claim:

The ornamental design for a power lawn mower, as shown and described.
